UNITED STATES PATENT OFFICE.

SALMON W. PUTNAM, JR., OF FITCHBURG, MASSACHUSETTS.

DESIGN FOR FRAME OF BOLT-THREADING MACHINES.

Specification forming part of Design No. 6,764, dated July 8, 1873; application filed January 24, 1873.

To all whom it may concern:

Be it known that I, SALMON W. PUTNAM, Jr., of Fitchburg, of the county of Worcester and State of Massachusetts, have invented or produced a new ornamental Design for the Frame of a Bolt-Cutting Machine; and do hereby declare the same to be represented in the accompanying drawing, which is a perspective view of such frame embodying the said design, which includes the pedestal A with its arched recess or passage B, the projecting arm C, and the curved open brace D, all formed, arranged, and provided with moldings, as shown.

The members of the pedestal are the brace a, the body b, and the capital c, the latter being surmounted by the tapering head d.

The body of the pedestal has an arched recess or passage, B, made in or entirely through it, transversely, and bounded by a boundary molding, f, as shown. The arm C has its cap molding to correspond in transverse section with the molding of the cap of the pedestal, all being as shown. The brace or strut is also open, and furnished with molding and edge moldings, as represented.

I claim—

The design, substantially as represented and described.

SALMON W. PUTNAM, JR.
